UNITED STATES PATENT OFFICE.

FRITZ ALDENDORFF, OF BERLIN-WILMERSDORF, GERMANY, ASSIGNOR OF ONE-FOURTH TO PAUL KOLISCH, OF NEW YORK, N. Y.

ELECTROMECHANICALLY-CONTROLLED TELEPHONE SYSTEM.

Application filed August 26, 1921, Serial No. 495,723, and in Austria September 8, 1918.

(GRANTED UNDER THE PROVISIONS OF THE ACT OF MARCH 3, 1921, 41 STAT. L., 1313.)

This invention relates to an electromechanically controlled system. The object of the invention is to simplify the construction of the connecting devices or switches used in such systems, to prevent the switches from establishing connections with wrong lines, and to enable the subscribers to obtain rapid connections in spite of the fact that only a comparatively small number of switches are provided.

A feature of the system is that a group or groups of switches with calling lines connected to, or associated with the contacts of their contact banks is provided with means by which, when the wiper of a switch is caused to brush over a row of the said contacts, only a certain one of these contacts is connected to battery, so that a current will flow through the said wiper and cause its motion to be stopped only when the said certain bank contact is reached.

The telephone system according to the invention may comprise a group (or groups) of talking connection calling line switches with calling lines connected to, or associated with, the contacts of their contact banks, and another group (or groups) of called line switches with called lines connected to, or associated with, the contacts of their contact banks, and primary means by which, when the wiper of a calling line switch is caused to brush over a row of its contacts, only a certain one of these contacts is connected to battery so that a current will flow through the said wiper only when it reaches the said certain bank contact, and secondary means by which when the wipers of a called line switch are caused to brush over a row of its contacts only a certain one of the called line finder bank contacts is connected to battery so that a current will flow through the said wiper of the called line finder when it reaches the contact that is connected to battery.

Another feature of the invention is that a plurality of calling lines may be simultaneously connected by transitorily engaged line finders to a plurality of numerical switches into which the calling subscribers send their selecting impulses and each of which numerical switches is temporarily or permanently

associated with one line finder of a group of talking connection line finders, and that means are provided by which only one contact in the bank of a particular talking connection line finder associated with an operated numerical switch can be connected to battery at one and the same time so that the movable contact of the said particular talking connection line finder can only receive current through the particular bank contact of this finder that corresponds to the calling line which sends its selecting impulses into the numerical switch associated with the said particular line finder.

A further feature of the invention is that a battery connecting device at all times connects battery only to a contact or contacts associated with one calling line, and to one talking connection line finder, and that the battery connecting device is common to a group of switches and only applies battery to a second calling line and talking connection line finder when the previous finder to which it applied battery has been properly set onto the contact of a calling line.

A further feature of the invention is that the transitorily engaged line finders of one and the same group have a common flat contact bank the talking connection calling line finders may also have a common flat contact bank. The transitorily engaged line finders are preferably provided with a vertical row of brush carriages which are adapted to be lifted simultaneously by a vertical bar. The talking connection calling line finders may have a vertical row of brush carriages, and when a connection is established a bar is rotated which selects the brush carriage and then lifts the same until its brushes reach a calling line.

A further feature of the invention is that the transitorily engaged calling line finders are provided with sub-group relays and that the talking connection calling line finders are provided with bar steering devices and with circuits so arranged that the bar steering devices are controlled by the sub-group relays. Controlling wires are provided by which the bar steering devices are controlled and these controlling wires lead directly

from the contacts of the sub-group relays to the contacts of the bar steering devices. Each calling line is preferably provided with a single separate steering wire for setting the talking connection calling line finders onto the calling line and the said steering wire is connected to battery by the common battery connecting device. The separate steering wire may also be used for 10 conducting current into a conversation meter. The arrangement according to the invention is preferably such that the calling lines send half their selecting impulses into transitorily engaged called line selectors 15 which mark the line to be called, whereupon a talking connection called line finder has its movable contacts set onto the marked wanted line.

An important feature of the invention is 20 that the wanted lines are first selected by wanted line selectors composed of a group of small switches whose number of bank contact points is smaller than the number of contact points in the banks of talking connection called line finders that are set onto 25 selected wanted lines by the said wanted line selectors. For example talking connection called line finders with contact banks for 100 wanted lines may be steered onto 30 any one of the 100 wanted lines by two small wanted line selectors each having only 10 bank contacts or contact sets.

The invention is shown by way of example in the drawing.

35 Fig. 1 shows a portion of a group of selectors having a common flat vertical contact bank or in other words a front view of portions of three selectors of the panel type. In this figure 3 brush carriages are shown 40 arranged between a pair of guide bars and behind a lifting bar adapted to lift the carriages to any desired set of bank contacts. The brush carriages and bars of the other two selectors whose bank contacts are represented in Fig. 1 are omitted.

Fig. 2 is a transverse section through the selector panel shown in Fig. 1. In Fig. 2 the lower rack end of the lifting bar and a holding pole associated with the same is 50 shown.

55 Fig. 3 is a perspective view of a portion of a selector panel with brushes cooperating with vertical contact bars let into the front surface of the panel and with individual bank contacts protruding from the layers of insulation between which longitudinal metal strips are embedded.

Fig. 4 is a front view of a portion of a 60 panel showing the manner in which the various units or divisions of the flat contact bank are held together by pairs of plates displaced with respect to each other.

65 Fig. 5 shows two brush carriages arranged one above the other, the lower brush carriage being lifted to such an extent that

an upwardly projecting extension tilts the brushes of the top brush carriage away from the contacts of the panel.

Fig. 6 is a perspective front view of a brush carriage with one brush broken away. 70

Fig. 7 is a perspective rear view of a brush carriage with the brushes omitted.

Fig. 8 is a top view of a bar steering device or switch comprising sets of vertical 75 springs.

Fig. 9 is a vertical section of Fig. 8 on the line V—W.

Fig. 10 is a modification of a brush holder.

Fig. 11 shows circuits by which the 80 brushes of a selector are caused to be set onto the bank contacts in a reliable manner.

Fig. 12 shows a preferred form of coupling roll used for lifting the lifting rods of the selectors. 85

Fig. 13 shows the circuits of the transitorily engaged calling line finders and of the battery connecting device by means of which the talking connection calling line finders are set onto the proper calling lines. 90

Fig. 14 shows the circuits of the talking connection calling line finders and of a group selector or numerical switch.

Fig. 15 shows the circuits of the transitorily engaged wanted line selectors, the 95 talking connection wanted line finders, and the battery connecting device by means of which the wanted line finders are caused to connect to the proper wanted lines.

The frame of a selector group consists of 100 vertical bars E, G of angle iron, of horizontal transverse bars F and four longitudinal bars or plates H, I, K, L. The bodies M of the coils of the coupling magnets or rolls P are supported on the longitudinal bar H 105 by means of nuts N (Fig. 1). Journalled in the longitudinal bar are the selecting rods or steering rods U of the various selectors. The coupling rolls are kept continuously rotating by a shaft R driven by a pulley Q. 110

The coils O which encircle the coupling rolls do not revolve but are kept stationary with the bodies M of the coils. The selecting rods in addition to gliding in holes in the longitudinal bar H are also journalled in the 115 longitudinal bars K and L. Near their top ends the selecting rods are provided with ratchet teeth e for rotary movement and near the lower ends they are equipped with round collars f adapted to be engaged by a pawl D so as to hold the rod in any position to which it may have been raised. The selecting rods are also equipped with selecting fingers g₁, g₂, which, when the rod is rotated by the corresponding rotary magnet S with 120 the aid of its armature T, the rotating pawl h and the rotary teeth e are caused to register with a tongue i₁, i₂ or i₃ etc. so as to be able to lift the particular brush carriage k₁, k₂ or k₃ respectively which is selected by ro-

125

tating the rod U. It will be understood that the fingers *g* are radially displaced with respect to each other in such a manner that according to the amount of rotation imparted 5 to the rod U the particular brush carriage that it is desired to select will be seized by a corresponding finger *g*. When the coil O belonging to a selecting rod is energized by an electric current the corresponding iron 10 coupling roll P is magnetized and attracts the iron rod lifter *j*. The friction which now ensues between the rod lifter *j* and the rotating coupling roll results in the elevation of the rod and of the brush carriage *k* selected. Thus, if the finger *g*₁ has been rotated into a position in which its outer end is beneath the tongue *i*₁ the brush carriage *k*₁ will be lifted. During its upward travel the carriage glides between two guide rods 15 *l*₁, *l*₂ and the brushes A, B, C, slide upon the conducting bars or strips *a*₃, *b*₃, *c*₃ (Fig. 3) and over groups of contacts *a*, *b*, *c*, until the proper set of contacts *a*, *b*, *c* is reached when the coupling roll will be deenergized. 20

25 During the upward travel of the selecting rod a holding pawl or detent D will slip from collar to collar *f* so that when the coupling roll is deenergized the rod will be held in its elevated position.

30 In order that the selecting rod may be elevated from each set of contacts *a*, *b*, *c* to the next without vibration and in a reliable manner special circuits shown in Fig. 11 are provided. The coupling roll P (Fig. 11) is energized in any suitable manner, as by the closure of the switch *m*. A current then flows from the positive pole of the battery through the armature *n* of the relay *o*, coupling roll P to the negative pole. The selecting rod U is now elevated in the manner already described and the brush C slides up 35 on the conducting strip *c* and from one contact *c*₁ to another. During the ascension of the brush C from the middle of a contact *c*₁ to the lower edge of the next contact *c*₂ the contacts *r*, *q* affected by the pawl D keep apart. But when the brush C ascends from the lower edge of the next contact up to a 40 point immediately beneath the middle of this contact the springs *q*, *r* are caused to make contact and a branch circuit is closed from the negative pole through P, *r*, *q*. Now if, during the time in which the brush ascends from the lower edge of the next contact *c*₂ to the middle of the same, the current path through the relay *o* (positive pole *o*, *c*₃, C, C₂, *t*—pole) is closed and the circuit from the positive pole through *m*, *n*, P to the negative pole is opened, the coupling roll 45 P will be energized in any case by a current from the positive pole through *q*, *r*, P to the negative pole until the brush C reaches the middle of the next contact *c*₂. At this moment the holding pawl D will slip in beneath the next collar *f* and open the contact springs 50

55 Since the relay *o* will be energized at this moment the coupling roll P will be deenergized and the brush C will stop on the middle of the contact *c*₂. If, on account of the inertia of the rod, the brush C should be tossed beyond the middle of the contact *c*₂, the brush and the rod will drop back and the latter will be held by the pawl D in a position in which the brush C will rest upon the middle of the contact *c*₂. 75

To restore the selecting rod to its normal position further current impulses are sent through the rotary magnet S. The rod is then rotated until a longitudinal groove in the rod reaches the holding pawl, when the rod being no longer held by the pawl D is dropped down into its normal position. The brush carriage, as *k*₁, now also drops until its holding arms *v* (Figs. 1, 6 and 7) fall upon the stops *r* on the guide rods *l*₁, *l*₂. 80 On the brush carriages one arm *v* is arranged at the rear and another arm *v*₂ at the front of the respective guide rod. The stops *r*, *r*₁ are arranged in a corresponding manner. By this arrangement it is made 85 possible for each brush carriage, as *k*₁, to be raised beyond the stops *r*₂, *r*₃ of the next highest carriage and up to the stops *r*, *r*₁ of the next highest carriage but one. In this way provision is made for the brushes of 90 each carriage to ascend into the range swept by two further carriages. 95

100 When a brush carriage is raised up to the level of the next carriage above it a striker *d*₁ of the former strikes against the lower surface of the brush holder *e*₁ of the next carriage in the manner illustrated in Fig. 5. The brush holder *e*₁ is then swung back on its pivot *f*₁ and the brushes A, B, C are tilted away from the contact panel. 105

110 The tongues *i* of the brush holders may also be bent in the form of an angle as shown in Fig. 10. The fingers *g* of the selecting rod will then brush against the surface *g*₁ of the tongue *i*₁ when the selecting rod is turned and will press the brushes A, B, C against the contacts or the contact panel. The pressure of the brushes against their contacts may be of any desired magnitude. 115

120 The panel-shaped contact bank is made up of metal strips *a*₁, *b*₁, *c*₁ . . . *a*₂, *b*₂, Fig. 3, which extend past all the selectors of the selector group. Each metal strip is separated from the next by a strip of insulation. The metal strips have projections *a*, *b*, *c* which jut out from the front surface of the bank and whose ends are bent downwards. The position of these projections is such that they lie in the paths of the brushes A, B, C. Extending at right angles to the contact strips *a*₁, *b*₁, *c*₁ . . . *a*₂, *b*₂, *c*₂ are conducting strips *a*₃, *b*₃, *c*₃ which are let into the front edges of the horizontal strips of insulation. Hence the brushes A, B, C 130

establish connections between the conductors bars a_3, b_3, c_3 , and the different contact groups or sets $a_1, b_1, c_1 \dots a_2, b_2, c_2$ according to the heights to which the brushes are raised.

- The contact banks are preferably made up of horizontal divisions as shown in Figs. 1 and 2. The metal strips and layers of insulation of each division are held together by pairs of plates $h, h_1 \dots h, h_1 \dots m_1$, Fig. 4. The pairs of plates of the various horizontal divisions are displaced with respect to each other in such a way that the plates of one division project into the gaps between the plates of the next division. All the divisions are held together in the manner shown in Figs. 1 and 2 between the longitudinal bars K, L by means of the rods l_1, l_2, l_3 .
- 10 The brush carriages travel between the guide bars l_1, l_2 and are provided with rolls n_1, n_1 to reduce friction. In order to obtain a powerful lifting effect with the coupling roll the rod lifter j is preferably made 15 in the shape of a blunt wedge and the iron discs at the ends of the rolls are shaped accordingly as shown in Fig. 12. The coils for magnetizing the rolls P are provided in substantially the same manner as explained 20 in connection with Fig. 1, the engagement between P and j being where the bevelled surfaces contact, the wedge j being so shaped as to clear with its face the magnetizing 25 coils.

- 30 The switches described above may be used for diverse purposes. For example they may be used to perform the functions of group selectors, connectors, line finders, trunk finders etc. in automatic or semi-automatic telephone exchanges.

- 35 In a switching arrangement according to the invention the afore-described switches may be provided with additional rod steering devices of the kind shown in Figs. 8 and 45 9 when the said switches are employed as calling line connectors for establishing talking connections with calling or called lines. In such cases the rod U is prolonged at its upper end and provided with a ring o_1 and 50 a projection p_1 . When the rod U is turned the projection p_1 presses back one contact spring r_1 after another in succession causing the springs r_1 to make contact with their associated springs q_1 . The insulating 55 body s_1 with its pairs of contact springs q_1, r_1 is screwed fast by screws t_1 upon the longitudinal bar H , Figs. 1 and 2.

- 60 Having now described the construction of the switching apparatus, I will proceed to describe a preferred circuit arrangement according to the invention.

- 65 A complete diagram is obtained by placing Figs. 13, 14 and 15 beside each other with Fig. 14 in the middle. In Fig. 13, I and II are two transitorily engaged calling

line finders arranged in a group with a common contact bank or panel as shown in Figs. 1 and 2. There may be any number of such transitorily engaged calling line finders. Their number will however be smaller than 70 that of the calling line connectors (Fig. 14) with which they are associated. P_1, P_5 are the coupling rolls and $A_1, B_1, C_1, D_1 \dots A_2, B_2, C_2, D_2$ are the various brushes of the transitorily engaged finders. The contacts a_1, b_1, c_1, d_1 and the conducting strips a_3, b_3, c_3, d_3 are constructed in the manner shown in Figs. 1 and 2. The horizontal divisions of the common contact panels comprise as many contact strips as are required 80 for 10 subscribers. The transitorily engaged finders I and II of Fig. 13 differ in their construction from the switches shown in Figs. 1 and 2 in that the conducting strips a_3, b_3, c_3, d_3 are each common only to one 85 horizontal division instead of to all the divisions of the panel and in that the fingers of the brush raising rods register at all times with all tongues of the brush carriages so that all the brush carriages are raised simultaneously 90 when the rod is elevated. In these transitorily engaged finders no rotation of the rod takes place. To restore the rod to its normal position a holding pawl 60 is withdrawn 95 from the teeth of a ratchet by a restoring magnet 45, whereupon the rod and all the brush carriages drop down into their normal position.

Associated with each transitorily engaged 100 finder I, II is a trunk finder III or IV respectively. In the illustrated circuit arrangement each trunk finder has six rotatable brushes. In Fig. 13 there is also shown a special line identifying or battery connecting device V which serves to prevent the 105 calling line connectors VI and VII, Fig. 14 from being set onto wrong lines. The calling line connectors or talking connection switches have a flat contact bank or contact panel in common with the transitorily engaged finders. But the calling line connectors differ from the transitorily engaged finders in that they are provided with rod steering devices S_1, S_2 and rotary magnets 110 155 by means of which the steering rods are 115 rotated in the desired degree. Fig. 14 also illustrates the circuits of a group selector VIII which is constructed as shown in Figs. 1 and 2.

Fig. 15 illustrates a wanted line selector 120 that is only used temporarily in establishing a talking connection, a wanted line connector IX, a trunk finder XI, a line identifying device for preventing the wanted line connectors from being set onto wrong wanted 125 lines.

The wanted line connector is constructed in the same way as the calling line connectors VI, VII. It is equipped with brush carriages each having four brushes $A_8, B_8, 130$

C_s , D_s and with a rod steering device S_s and a rotary magnet by which the selecting rod is caused to select the proper brush carriage.

- 5 The wanted line selector X consists of a number of small switches XIV, XV each provided with a separate rotary magnet 291, 292, each individual switch, XIV, XV is adapted to select any line in a sub-group 2'', 3'', 4'', 6'' consisting of, say, ten lines. The particular individual switch or sub-group containing the desired line is picked out by a sub-group selecting switch XIII. Hence, in cases in which the subscriber's groups comprise 15 100 subscribers' lines each wanted line selector may be composed of ten individual switches with ten contact points each and a sub-group selector with ten contact points. The wanted line selector may however be 20 composed of two individual switches with ten contact points each, or, under certain conditions, even of only one such ten points switch as will hereinafter be more fully described.
- 25 For each group of 100 lines two or three or more wanted line selectors and ten wanted line connectors may be provided. Associated with each wanted line selector is a trunk finder XL. For each group of 100 30 lines a line identifying or battery connecting device XII is provided which is common to all the wanted line selectors of the group.

Associated with each calling line connector VII is a group selector VIII. The 35 number of group selectors may however be smaller than the number of calling line connectors if auxiliary connectors or trunk finders are interposed between the calling line connectors and the group selectors.

- 40 For each group of one hundred subscribers about two or three transitorily engaged line finders I, II are provided and about ten calling line connectors. In cases in which the subscribers groups comprise 45 more or fewer subscribers lines the number of line finders and connectors will be correspondingly larger or smaller. Associated with each transitorily engaged or quick acting line finder I, II is a link circuit finder 50 or trunk finder III, IV. Each group of transitorily engaged finders is provided with a line identifying or battery connecting device V.

55 The lines 2, 3 of the subscribers 1 are connected to contact strips 2'', 3'' which extend past all the wanted line connectors IX. Associated with each subscribers line is a test wire 5 for the transitorily engaged finders and the calling line connectors, a 60 test wire 4'' for the wanted line selectors and the wanted line connectors, a stopping and meter wire 6', and a stopping wire for the wanted line connectors. Hence four wires 2'', 3'', 5, 6 (Fig. 13) extend past each group 65 of calling line connectors and four wires

2'', 3'', 4'', 6'' extend through each group of wanted line connectors (Fig. 15).

All the other details of the circuits will appear in the following description of the operations which occur in establishing a 70 talking connection between two subscribers.

It will be assumed that the subscriber No. 1 desires to connect his line with that of the subscriber No. 111.

The calling subscriber 1 in raising his receiver from the hook closes his line circuit and a current will flow from the positive pole of the exchange battery through the upper winding of the line relay 7, contact 12 of the cut off relay, 2, 1, 3, contact 8 of the 80 cut off relay, lower winding of the line relay 7 to the negative pole. The line relay 7 closes its contacts 10 and 15 and opens the contact 14. At the contact 10 circuits are closed which include the coupling coils P^1 , P^5 of the transitorily engaged finders I, II and the rotary magnet 16 of the line identifying device V. These circuits may be traced from the positive pole through 10, P^1 , 44, 49, to the negative pole; from the 90 positive pole through 10, P^5 , 72, 71 to the negative pole; and from the positive pole through 10, 91, 16 to the negative pole. All the brush carriages or sets of brushes A, B, C, D of the quick acting finders will now be 95 caused to travel upwards over the contact bank by the continuously revolving excited coupling coils P^1 , P^5 . The rotary magnet 16 imparts rotary movement to the wipers 17, 18, 19, 20.

The steering rod of the one quick acting finder, say II, is displaced with respect to the rod of the other finder I in such a way that its brushes are one step behind the brushes of the first finder. By this measure 105 the contingency is prevented from arising that both finders strike upon the same calling line at the same moment.

By the closure of the contact 15 the positive pole of the battery is connected through 110 the winding 9 of the cut off relay and through 15 to the test wire 5. By the opening of contact 14 the calling line is made to test busy to the wanted line selectors because current will be prevented from flowing from 115 a wanted line connector through a wire 4'' and through the cut off relay 9 to the positive pole.

As soon as a brush, say C^1 , of a quick acting finder reaches the test contact c^1 of a 120 test wire 5 connected to the positive pole a current will flow from the negative pole through the contact 21 of the relay 26 of the trunk finder III, wire 40, contacts 41, 46, 51, relay winding 45, conducting strip c^3 , brush C^1 , contact c^1 , test wire 5, contact 15, cut off relay 9 to the positive pole. The relays 45 and 9 are both excited. The relay 45 closes its contacts 42, 43 and opens its contacts 41 and 44. By the opening the contact 41 the 125 130

connection of the remaining test relays 50 with the wire 40 and the negative pole is broken and from this moment no other test relays can be energized. The circuits of the 5 test relays 45, 50 of each quick acting finder are arranged in such a manner that no more than one test relay can ever be energized at the same moment. If it should happen that two relays 45, 50 are simultaneously energized the second relay 50 will be immediately deenergized again a moment later by the opening of the contact 41 of a first relay 45. But if the relay 50 has once pulled up its armature no subsequent energization of the relay 45 can take place because this latter will be cut off from the battery supply lead 71 by the opening of a contact 46.

When the relay 45 has closed its contacts 20 42, 43 in the manner described and has opened its contacts 41, 44 a current flows from the negative pole of the battery through 21, 40, 42, relay 52, to the positive pole and another current flows from 40, 25 through 43 and apart of the winding 45 through c^3 , C^1 , c^1 and through the cut off relay 9 to the positive pole. By the application of the negative pole or the wire 40 to a few turns of the winding 45 the test potential on the test wire 5 is lowered in a known manner and the busy condition of the calling line is thus established to prevent its seizure by other quick acting line finders.

By the opening of the contact 44 the coupling coil P^1 is deenergized so that the brush carriages of the quick acting finder I are all stopped. On the simultaneous energization of the cut off relay 9 and the opening of the contacts 8, 12 of this relay the line relay 7 is deenergized. A relay 68 which was energized on the closure of the contact 10 of the line relay will now be deenergized if no other line relays are energized and it will close its contacts 69, 70. The contact 70 40 closes a circuit which extends from the negative pole through 71, 72, 70, release magnets 73 and through the restoring relay 75 and the off normal contact 74 to the positive pole. The relay 75 closes a locking circuit for itself at its contacts 76 and now keeps the circuit (negative pole, 76, 75, positive pole) of the release magnet closed until the steering rod of the quick acting finder II drops back into its normal position and the circuits of the magnet 73 and the relay 75 55 are opened by the off normal switch 74.

The energization of the release magnet 45 or of the relay 68 of the quick acting finder I that has connected to the calling line 2, 3 60 does not take place at this time because the connection between the contact 69 and the negative pole is broken at the contact 44.

By the closure of the contact 42 a circuit is closed from the negative pole through 21, 65 40, 42, relay 52, to the positive pole. The

relay 52 opens the contact 51 and thus interrupts the indirect connection which would extend from 40 through the rear portion of the winding 45 and through 53 to the winding 50.

By the closure of the contacts 60, 61 the calling line 2, 3 is connected through the brushes A^1 , B^1 , contacts 60, 61, wires 78, 79 wipers 32, 34, to the wires 82, 83 which lead to the group selector VIII or the calling line connector VII.

The trunk finders III, IV always keep their associated finders I, II, connected to a free calling line connector VI, VII by means of circuits which will be hereinafter more 30 fully described. The arrangement may also be such that a trunk finder is started at the same moment as its associated line finder and then connects its line finder to the first free trunk found by its wipers.

By the closure of the contact 63 a circuit is prepared for the stopping of the wipers 17, 18, 19, 20 of the identifying device V on the wires 86, 87, 88, 89 that lead to the quick acting finder I or to the associated 35 trunk finder III. When the wipers 17 strikes upon the wire 86 a current flows from the positive pole through the closed contact 63, wire 86, wiper 70 and through the relay 90 to the negative pole. The relay 90 opens 40 the circuit of the rotary magnet 16 and its contact 91 so that the wipers 17, 18, 19, 20 are stopped. The contacts 92, 93, 94 are closed by the relay 90. The contact 92 prepares a circuit which operates to stop the 45 rotation of the brush lifting rod or of the arm S^2 attached to the rod of the calling line connector VII to which the line finder I is connected by the trunk finder III.

The contact 93 prepares a circuit which causes the brushes of the calling line connector VII, lifted by the coupling coil P^2 to stop at the proper calling line. The contact 94 cooperates with the contacts 92 and 93 in the said prepared circuits which control the setting operation of the rotary switch S^2 of the brush lifting rod and the lifting operation by which the brushes of the calling line connector are set onto the proper calling line.

The manner in which the calling line 2, 3 is connected through the quick acting line finder and the associated trunk finder III to the wires 82, 83 of the group selector VIII has already been explained. As soon as this connecting operation is completed a current flows from the positive pole to the left winding of the line relay 100, contact 101, of the relay 103, 83, wiper 34, of the trunk finder III, 79, 61, a^3 , A^1 , $2''$, 2, subscriber station 1, 3, 3'', b^1 , B^1 , b^3 , 60, 78, 82, contact 106 of the relay 103, right hand winding of the line relay 100 to the negative pole. The line relay closes its contacts 118, 120 and opens the contacts 119, 121. A 130

current then flows from the negative pole through 118, release relay 112, resistance 113 to the positive pole. The change over relay 114 which was energized by a current from 5 the negative pole through 118, 114, 115 to the positive pole is short circuited by a contact 120 so that for the time being its contacts 116 and 117 remain in their normal positions. The release relay 112 closes its 10 contacts 109, 110 and opens the contacts 107, 108 and 111. At the contact 109 the release relay closes a locking circuit for itself which is maintained until the contact 118 is closed at the finish of the conversation. A current 15 also flows at this time from the positive pole through 110, 110', 141, rotary magnet, 155, of the calling line connector, interrupter 160 to the negative pole. The rotary magnet now turns the brush lifting rod of the 20 calling line connector and this rotary motion is accompanied by the rotation of the rotary control switch S^2 which closes a fresh pair of contacts 154 at each rotary step until a finger of the brush lifting rod registers with 25 the proper brush carriage. As soon as this happens a current flows from the negative pole at the identifying device V (Fig. 13) through the contact 94 and through 20, 89, 35, 85, relay 144 of the calling line connector, 30 160, pair of contacts 154, steering wire 161, contact 64 of the subgroup relay 52, wire 87, 18, 92, to the positive pole. The relay 144 of the rotary control switch S^2 is energized and opens the contacts 141, 147 whilst 35 it closes the contacts 142, 143, 145 and 146. At the contact 141 the circuit of the rotary magnet 155 is opened and at the contact 142 the coupling coil circuit P^2 is closed (positive pole, 110, 142, 153, P^2 , negative pole). If 40 during the operation of the rotary control switch S^2 other brush lifting rods with their rotary control switches S^1 are rotated no such rotary control switch can be stopped on the wire 161 because it will not have any 45 battery connection extending from the minus pole through 94 of the identifying device and through 91', 35', 85' to its relay 144. It is thus seen that the only rotary control switch that can be set onto the line 161 is 50 one that has been associated with the wire 161 by means of a quick acting finder or a subgroup relay 52 and whose lead to its relay 144 has been connected by an identifying device V to the negative pole. Thus all possibilities of wrong connections being established by the calling line connectors are 55 precluded by the identifying device V which applies the battery to only one contact in the contact bank of a started calling line connector and to the hunting wiper or relay 144 of this connector at a time. 60 The relay 144 closes a locking circuit for itself at the contacts 143, 145 which extends from the negative pole through 109, 145, 143, 157 to the positive pole. By the contact 146 the relay 144 connects the negative pole to the relay 148. On the brush D^7 now rising up to the contact D^2 of the stopping wire 6 of the calling line a current will flow through the relay 148 from the negative pole 65 through 109, 146 winding 148, wire 161', lead d^6 , brush D^7 , contact d^8 , stopping wire 6, contact d^1 of the quick acting finder I, brush D^1 , contact 62, 88, wiper 19 of the line identifying device V, 93, resistance 95 to the 70 positive pole. The hunting brush D^7 is precluded from finding any stopping wires connected with the positive pole of the battery excepting the stopping wire 6 of the subscribers line whose call gave rise to the starting of the calling line connector VII, because the said starting wire 6 is the only one which is connected through the contact 93 of the identifying device V to the positive pole of the battery. 75 80 85 90 95 100 105 110 115 120 125 130

As soon as the relay 148 is energized in the manner described a new circuit is closed for its right hand winding which extends from the negative pole through 109, winding 148, 149, 162, c^6 , C^7 , c^2 , 5, 13, cut off relay 9 to the positive pole. The coupling coil P^2 is deenergized at the contact 153 and the calling line 2'', 3'' is connected through the brushes A^7 , B^7 , connecting strips a^2 , b^2 , contacts 151, 152, to the wires 82, 83 and the line relay 100. At the contact 150 the relay 148 closes a starting circuit for the trunk finder III. This circuit extends from the positive pole through 150, 84, 36, relay 37 to the negative pole. The contacts 38, 39 are closed the latter completing the circuit of the release magnet 45 (negative pole, 39, 35, 45, positive pole) and the former closing a circuit of the relay 26 (negative pole, 38, 26, positive pole). The quick acting finder I is restored to normal by its release magnet whilst the trunk finder III is caused by the deenergization of the relay and the closure of the circuit of its rotary magnet 30 (negative pole, 29, 23, 30, positive pole) to impart rotary motion to its wipers until these latter strike upon a calling line connector or trunk that is neither engaged for a conversation nor has been seized by another trunk finder IV. When the wipers of the started trunk finder have found such a trunk or calling line connector the contact 147 of the relay 144 and a contact 111 of the group selector associated with the disengaged calling line connector will both be found closed. A current will then flow from the positive pole through 111, 147, relay 140, 81, 32, contact 24 of the relay 26 to the negative pole. The relay 140 is then energized. If the calling line connector has not been seized by any other trunk finder a current will flow from the positive pole through 139, 80, 31, 22, relay 27 to the negative pole. The relay 27 is energized. But thus energization could not 130

take place if another trunk finder such as 5 IV had already seized the same calling line connector because then a current would flow direct through 31', and a back contact 21' of the other trunk finder to the negative pole of the battery instead of first flowing through the relay 27 of the hunting trunk finder.

But if the relay 27 is energized the circuit 10 of the rotary magnet 30 is opened at the contact 29. At the contact 28 the locking circuit of the relay 26 (positive pole, 26, 25, 15 28, negative pole) is opened. Hence all the parts of the trunk finder III and the quick acting line finder I return to their normal positions and the associated trunk finder connects its quick acting finder I to a free unseized calling line connector.

On the energization of the relay 26 the 20 negative pole of the battery was disconnected at the contact 21 from the wire 40 and therefore also from the subgroup relays 45, 50 of the released quick acting finder I, so that this finder, in dropping back to its 25 normal position, is prevented from establishing a connection with any line whose wires 5 may be in a calling condition.

During the period in which the calling 30 line connector VII was set onto the calling line by a prior rotary motion of the rotary control switch for the purpose of selecting the subgroup of the calling subscriber and by a subsequent elevating motion caused by the coupling coil, the calling subscriber 35 may have been able to send selecting impulses through the line relay 100. All the selecting impulses which may still have to be sent to the relay 100 after the calling line connector has been set onto the calling line, 40 will flow without being interfered with in any way over the following path: from the positive pole through the left winding of relay 100, 101, 83, 152, 170, a², A⁷, a⁴, 2'', 2, subscriber station 1, 3, 3'', b⁴, B⁷, b², 171, 151, 45 52, 106, right winding of the relay 100 to the negative pole.

At each interruption of this circuit during the dialling operation the armature of the relay 100 falls back. The contacts 118, 50 120 are opened and the contacts 119, 121 closed. As soon as the contact 121 is opened the by-path which short circuits the change over relay 114 is opened so that the change over relay is energized to close its contact 116 and open the contact 117. During the vibration of the armature of the relay 100 effected by the selecting impulses the momentary short circuitings of the change over relay 114 effected by the contact 120 60 do not affect the energization of the change over relay so that it keeps its armature attracted.

At each retraction of the armature of the relay 100 a current impulse flows from the

negative pole through 109, 121, 116 and to 65 rotary magnet 172 to the positive pole. The brush moving rod of the group selector is thus rotated until one of these fingers registers with the proper brush carriage, which in this case is the carriage which supports 70 the set of brushes A⁵, B⁵, C⁵. The first current impulse from the negative pole through 109, 121 and 116 also flows through the relay 123 to the positive pole. The right winding of this relay closes a locking 75 circuit for itself (positive pole, right winding 124, 109, negative pole) which remains closed up to the end of the connection. By the closure of its contact 122 the relay 123 prepares a circuit for the coupling coil P₃. 80

When all the selecting impulses (in this case one impulse, because the first hundred is being selected) have been sent in the relay 100 maintains its armature in its attracted position. The contact 120 now keeps the 85 change over relay 114 short circuited again so that this relay lets its armature fall back to open the contact 116 and close the contact 117. A current then flows from the negative pole of the battery through 117, 90 122, 128, P₃ to the positive pole. The coupling coil P₃ being energized now causes the brush moving rod to rise so that the brushes A⁵, B⁵, C⁵ slide upwards over the contact bank. The upward motion of the brushes 95 continues until they reach a trunk line 200, 201, 202 which is not engaged for a conversation but which is connected by a trunk finder XI to an idle wanted line selector X (Fig. 15). A current then flows from the negative pole through 109, 180, test relay 125, 100 conducting strip 181, test brush C⁵, test wire 202, lower winding of relay 250 (Fig. 15), wiper 244, relay contact 252, 264, wiper 290 of the wanted line selector to the positive 105 pole and battery. The test relay 125 and the relay 250 are energized. The former closes its contact 126 and the latter closes its contact 221. The test relay 125 short circuits the upper part of its winding and 110 thus lowers the potential on the test wire 202 so as to make the seized trunk test busy, whereby other group selectors are prevented from seizing the trunk 200, 201, 202. If no wanted line selector X had been connected 115 with the trunk line the group selector would not have been able to seize it because there would then have been no energizing circuit for the test relay 125 through the wiper 244 of the trunk finder. In a similar manner, 120 no circuit would have been established for the test relay if the wanted line selector had been engaged because the test circuit would then have been open at the contact 264 or at the wiper 290. This will be more 125 fully explained later.

As soon as the test relay 125 is energized it opens the circuit of the coupling coil at its

contact 128. The branch circuit of the coupling coil (negative pole, q , p , P^3 , positive pole), which, as was previously explained, serves to effect the proper setting of the contact brushes onto the middle of each set of contacts is also interrupted when the test relay 125 is energized so that the brush carriage or brushes A^5 , B^5 , C^5 are stopped on the trunk 200, 201, 202. At its contact 127 the test relay closes a circuit for a relay 103 which extends from the positive pole, through 132, 127, 103 to the negative pole. This relay connects the wire 83 of the trunk to ground connected with the positive pole 15 of the battery and the other wire 82 through its contact 105 to the wire 184 so that a current will now flow from earth through 102, 83, 152, 170, a^2 , A^7 , a^4 , 2'', 2 (Fig. 13) subscriber station 1, 3, 3'', b^4 , B^7 , b^2 , 171, 151, 20 82, 105, 184, 129, 182, B^5 , 201, 306 (Fig. 15) 243, 251, line relay 269 of the wanted line selector to the negative pole.

At its contact 104 (Fig. 14) the relay 103 closes a circuit for the left winding of the 25 relay 100 (negative pole 104, 100, positive pole) and thus prevents the deenergization of the relay 100, which would result in the restoration of the group selector and the calling line connector to their normal positions as will be hereinafter described.

The line relay 269 of the wanted line selector, which, as has just been pointed out, is energized by a current flowing over the calling subscribers line, closes its contacts 35 270, 272 and opens the contacts 271, 273. At the contact 270 the circuit of the release relay 268 is closed, this circuit extending from the negative pole through 270, 268, resistance 278, to the positive pole. The release 40 relay closes a locking circuit for itself at its contact 267 (negative pole, 268, resistance 278, positive pole). A circuit is also closed for the change over relay 275 (negative pole, 270, 275, 279, positive pole) but the change over relay is kept short-circuited for the time being by the contact 272. The release relay 268 closes its contacts 267, 274 and opens its contacts 264, 265, 307 whilst the change over relay remains deenergized.

50 The calling subscriber now sends in his tens selecting impulses for the purpose of setting the wanted line selector unto the proper tens group. At each interruption of the dialling circuit the line relay 269 is deenergized and the contact 272 is opened to remove the short circuit about the change over relay 275. This relay is energized (negative pole, 267, 275, 279, positive pole) and closes its contact 276 whilst opening the contact 277. As long as the dialling impulses flow through the line relay 269 its armature will vibrate and cause momentary short circuitings of the release relay by the contact 271 and similar short circuitings of

the change over relay 275 by the contact 272. 65 But these momentary short circuitings do not suffice to deenergize the said relays so that they keep their armatures attracted. At each closure of the contacts 271, 273 a current impulse flows from the negative pole 70 through 267, 273, 276, 285, rotary magnet 287, 274, 309, wiper 290 to the positive pole. Each said impulse causes the subgroup selector XIII to be rotated one step, and this step by step movement continues until the 75 proper subgroup (which in this case is the first subgroup or tens group or the first units switch which selects the lines within the first tens group) is reached. The wiper 288 then establishing connection with the rotary 80 magnet 292 of the first units selector XV and the wiper 289 establishing connection with the stopping wire or guide wire 310 that leads to the rotary control switch S^3 of the wanted line connector IX. The 85 wiper 290 is set onto a segment 312 which is connected with the magnet 287 or the relay 263. The wiper 290 and the segment 312 serve to restore the wanted line selector to its normal position as soon as the selector 90 has performed its function of setting or guiding a wanted line connector onto the proper wanted line.

When the first tens selecting impulse is sent in the current flows not only through 95 the rotary magnet 287 but also from the negative pole through 267, 273, 276, relay 282 to the positive pole. The relay 282 closes a locking circuit for itself at its contact 281 (negative pole, 267, 314, 281, 282, 100 positive pole) and at its contact 280 it prepares a circuit for the relay 283.

After the tens impulses have been sent in, i. e. after the first tens impulse in the present instance, the line relay 269 keeps its armature attracted. The change over relay 275 is then short circuited by the contact 272 so that it is deenergized and causes a current to flow from the negative pole through 267, 277, 280, relay 283, to the positive pole. 110 The relay 283 is energized and closes a locking circuit for itself at its contact 284 (negative pole, 267, 284, 283, positive pole). At its contacts 285, 286 the relay 283 disconnects the wire 315 from the rotary magnet 287 and connects it to the wiper 288. The calling subscriber now sends in the units selecting impulses causing the armature of the line relay 269 to vibrate. The change over relay 275 is energized again and current impulses flow from the negative pole through 267, 273, 276, 286, 288 to the rotary magnet 292 of the first units selector, i. e. to the selector with which the wiper 288 established connection, and to the positive pole. Since the calling subscriber desires to connect with the line number 111 he will only send in one units selecting im-

pulse, so that the rotary magnet 292 only receives one current impulse and the wipers 315, 316 are set onto the test wire 4' and the guide wire 6' associated with the desired 5 subscriber's line.

The line relay now maintains its contacts 270, 272 closed again so that the change over relay 275 is deenergized again and closes its contact 319 to connect the negative pole 10 through 267, 319 to the test relay 293. If the selected line is free the test relay will be energized by a current which flows from the negative pole through 267, 319, 293, 316, test wire 4' and then through the contacts 15 of the line relay and through the cut off relay associated with the called line (the said relay being similar to the relays 14 and 9 (Fig. 13) of the calling line) to the positive pole. If the called line is already engaged 20 by another wanted line selector the potential of the test wire 4' will not suffice to energize the test relay 293. If the wanted line should just happen to be calling another subscriber the potential on the test wire 4' 25 will also be lowered by a test relay 45 or 50 (Fig. 13) of a transitorily engaged line finder or by the relay 148 of a calling line connector (Fig. 14) to such an extent that the said potential will not suffice to energize 30 the test relay; or if the wanted line that is just in the act of calling another line has not yet been connected to a group selector by a quick acting line finder or a calling line connector, the contact 14 of the line relay of 35 the said wanted line will be open so that the test relay 293 of the wanted line selector testing the wanted line will not be energized because its circuit is open.

But if the test relay 293 is energized in 40 the manner described it will close the contact 295 and lower the potential on the test wire 4' to such an extent that no other wanted line selector will be able to connect to the selected line.

45 It has now to be mentioned that, when the line relay 269 and the release relay 268 were energized a circuit was closed from the negative pole through the interrupter 266, 391, 330, 300, rotary magnet 305 to the positive pole. The rotary magnet 305 rotates the wipers 296, 297, 298, 299 of the identifying device XII until the wiper 296 strikes upon a wire 331 which is connected by the contact 294 of a test relay to the positive pole. The relay 301 attracts his armature and closes the contacts 302, 303, 50 304 whilst opening the circuit of the rotary magnet 305 at the contact 300. By the contacts 303, 304 the negative pole of the battery is connected to the two guide wires or stopping wires 310 and 6' (by way of 304, 55 299, 289 to 310; or through 303, 298, 315 to 6) and the contact 302 connects the positive pole of the battery to the guide wire 332 (through 297, 246 to 332).

By the contact 294 an energizing circuit is closed for the rotary magnet 333 of the rotary control switch S³ which circuit extends from the positive pole 294, 247, 232, 333, interrupter to the negative pole. The 70 rotary magnet 333 now turns the brush lifting rod until the pair of contacts 336 is closed which is connected to the tens guide wire 310 that is the guide wire that leads to the subgroup selector XIII. A current 75 then flows from the positive pole through 302, 297, 246, 332, relay 234, contact springs 336, subgroup or tens guide wire 310, wiper 289 of the wanted line selector, wiper 299 of the identifying device 304 to the negative 80 pole. Since the relay 234 of only one single one of all the called line connectors is connected to the positive pole, and of all the tens guide wire only a single one 310 is connected to the negative pole only the one 85 relay 234 of the wanted line connector that is connected to the identifying device can be energized even if several wanted line connectors are operated at the same time. The relay 234 closes its contacts 233, 235, 90 236 and opens the contact 232 and thus the circuit of the rotary magnet 333. At the contact 233 the circuit of the coupling coil P⁴ is closed (positive pole 294, 247, 233, 242, P⁴, negative pole) and the coupling coil now 95 causes the brush lifting rod to be elevated so that the selected set of brushes A⁸, B⁸, C⁸, D⁸ travel upwards and wipe past the contacts of the contact panel or bank until the guide circuit brush D⁸ reaches the units 100 guide wire 6' associated with a line of the wanted subscriber No. 111. Since the units guide circuit relay 237 of only a single one of the wanted line connectors of the particular group is connected through 302, 297, 105 246, 332, 236 to the positive pole and only the one units guide wire 6' of the wanted line No. 111 is connected by the identifying device XII to the negative pole (through 303, 298, 315), it is only possible for the one 110 relay 237 of the particular wanted line connector that is connected to the identifying device to be energized. The relays similar to 237 of other wanted line connectors cannot be energized by a current through the 115 units guide wire 6'. The relay 234 had closed a locking circuit for itself which extended from the positive pole through the contact 222 of the relay 250, 341, 235, 234, 336, 310, 289, 299, 304, to the negative pole. The relay 237 is now energized by a current 120 from the positive pole through 222, 341, 235, 236, 237, guide circuit brush D⁸, guide circuit contact d⁸, guide wire 6', 315, 298, 303 to the negative pole. The relay 237 125 closes its contacts 238, 239, 240, 241 and opens a circuit of the coupling coil P⁴ at the contact 242. The branch circuit (positive pole q¹, p¹, P⁴, negative pole) is also opened as soon as the brush D⁸ reaches the 130

middle of the contact d^9 , and the set of brushes A^8 , B^8 , C^8 , D^8 stops on the contacts a^9 , b^9 , c^9 , d^9 of the selected line No. 111.

By the contact 238 the lower winding of the relay 237 is included in a circuit which contains the cut off relay of the selected line, this circuit extending from the negative pole through 395, lower winding, 238, 239, 343, C^8 , c^9 , test wire 4', contact 14 of the line relay and the cut off relay 9 of the selected subscriber (Fig. 13) to the positive pole of the battery. The resistance of the lower winding of the relay 237 is such that the potential on the test wire 4' is lowered sufficiently to prevent the wanted subscriber line from being connected to or seized by a quick acting finder.

The contact 240 of the relay 237 closes a circuit for the relay 204 which extends from the negative pole to 240, 340, 225, 204, interrupter 208 to the positive pole and the relay 259 of the trunk finder XI is also energized by a circuit extending from the negative pole through the contact 240 of the relay 237, 381, 249, 259 to the positive pole. By means of its contact 205, 206 the relay 204 alternately connects the ringing current generator 207 and the ringing cut off relay 209 to the line 380 that leads to the called subscriber No. 111, and the relay 259 closes a circuit for the rotary magnet 382 of the trunk finder XI, this circuit extending from the negative pole through 258, 254, 382 to the positive pole. The brushes or wipers 243, 244, 245, 246, 247, 248, 249 are now moved on until the wiper 245 strikes a wire 384 that leads to a wanted line connector which is neither seized by a group selector nor a second trunk finder and which is not engaged for a conversation. If the wanted line connector has been seized by a group selector the contact 224 will be open; if the wanted line connector is being used for a conversation a busy condition will be established by the opening of a contact 335. The circuit leading from the negative pole through 253, 245, 384, relay 229, 335 and to 224 to the positive pole will under these circumstances, not be closed. But as soon as the wiper 245 strikes a wire 384 which extends through closed contacts 335, 224 to the positive pole the relay 229 is energized. It closes a circuit leading from the positive pole through the resistance 231 and through 230, 383, 248, 256, relay 257 to the negative pole if the wanted line connector has not been already seized by another trunk finder; for in such a case the current, instead of flowing through the relay 257, would pass through the contact 255 of the other trunk finder to the negative pole. Hence, in a case like this, the relay 257 would remain deenergized. But when a wanted line connector that is neither being used for a conversation nor has been seized by any switch, is found the relay 257 is energized

in the manner described. The circuit of the rotary magnet 382 and of the relay 259 is opened at the contact 258 and the wipers 243 to 249 stop on the contacts leading to the free wanted line connector and thus seize it. 70

It must now be mentioned that as soon as the relay 259 was energized to open the contact 251, the line relay 269 was deenergized. This relay then closes the contact 271 and thus short circuited the release relay 268 75 which closed the contacts 265, 307 and opened the contact 274. The opening of the contact 267 results in the deenergization of the change over relay 275 and the relays 282, 283. 80

Restoring impulses now flow from the negative pole through the interrupter 266, 265, 261, 288 through 292 to the positive pole so that the wipers 315, 316, 317 of the particular units selector used, are stepped forward until the wiper 317 reaches its normal position in which it makes connection with the negative pole, a current then flows from the negative pole through 317, 386 and through the wipers 387 of all the other units 90 selectors which are in their normal positions and through 388, relay 263, segment 312, wiper 290 to the positive pole. The relay 263 immediately opened the circuit of the magnet 292 at the contact 261 and at its contact 262 it closes the circuit of the rotary magnet 287 which extends from the negative pole to the interrupter 266, 307, 262, 287, 312, 290 to the positive pole. The rotary magnet 287 now steps the wipers 288, 289, 290 of the sub group selector XIII round until the wiper 290 reaches its normal position and opens the circuit of the relay 263 and the rotary magnet 287 by leaving the segment 312. Since the test relay 293 was 105 also immediately deenergized on the deenergization of the release relay and the opening of the contact 267, all the parts of the wanted line selector will now have been restored to their normal positions. The wanted line selector will now also have been connected to a free wanted line connector in the manner already described and can be used for setting up a new connection. 110

The ringing current periodically connect ed to the wanted line by the relay 204 flows from the negative pole of the ringing current generator 207 through 205, 210, 380, wiper A^8 , a^9 , wire 2' to the called subscriber and back to $3'$, b^9 , B^8 , 390, 216 to the positive pole. As soon as the called subscriber responds and the contact 206 is closed a current flows from the negative pole through 241, relay 209, 206, 210, 380, A^8 , a^9 , 2', called station back through $3'$, b^9 , B^8 , 390, 216 to the positive pole. The relay 209 is energized and closes the contact 203 whereby a relay 217 is energized by a circuit extending from the negative pole through 203, left winding 120 217 to the positive pole. The relay 217 125

closes its contact 218 to energize the relay 227 by a circuit extending from the negative pole through 218, 227 to the positive pole. By this means a circuit is closed which extends from the positive pole through 222, 226, right winding of the relay 227, relay 213 to the negative pole. The relay 213 closes its contacts 211, 212, 214, 215 and opens its contacts 210, 216. The ringing relay 204 is cut out at the contact 225 and the ringing cut off relay 209 is disconnected at the contact 210. At the contacts 212, 214 a new circuit is closed for the relay 217 which extends from the positive pole to the left winding of 217, 214, 390 to the wanted subscriber and back through 380, 212, right winding of 217 to the negative pole. At the same time a circuit which extends back to the group selector is closed this circuit extending from the negative pole through the right winding of 217 and through 212, 211, 200, A₅, 183, 134, lower winding of relay 135 to the positive pole. This circuit which is the metering circuit energizes the relay 135 which closes a locking circuit for itself at the contact 136 (positive pole, relay 131, 135, 133, 180, 109, negative pole) and energizes the relay 131 whilst closing the contact 137. This contact directly connects the positive pole to the wire 161' and the meter 11 of a calling line is then actuated by a current which flows from the positive pole through contact 137, 161', d⁶, D⁷, d², 6, meter 11 (Fig. 13) to the negative pole. The conversation is thus counted.

The relay 131 opens the contacts 132, 134, 129 and closes 133, 130. By the opening of the contact 132 the relay 103 is deenergized to close its contact 101, 106. Current is now again fed through the windings of the relay 100 to the transmitter of the calling subscriber and voice currents now flow from the calling to the called subscriber over the following circuit: 1, 2, 2'' (Fig. 13 and 14), a⁴, A⁷, a², 170, 152, 101, condenser k₀, 183, 183, A⁵, 200, 211 (Fig. 15), 380, A⁸, a⁹, 2', wanted subscriber back over 3', b⁹, B⁸, 390, 215, 201, B⁶, 182, 130, condenser, 106, 82, 151, 171, b², B⁷, b⁴, 3'', 3, 1.

If the wanted subscriber replaces his receiver first at the end of the conversation the transmitter fed relay 217 (Fig. 15) in the wanted line connector is deenergized to close a contact 219 whereby the negative pole is directly connected through 219, 228 to the end of the winding of the relay 250 and this relay is short circuited so that its armature drops back. By this means a circuit for the rotary magnet 333 of the rotary control switch S³ is closed, this circuit extending from the positive pole through 223, 334, rotary magnet 333, interrupter through the negative pole, and causing the rotary magnet to turn the brush lifting rod until it reaches its normal radial position in which the contacts 334 are opened to deenergize the rotary magnet 333. The brush lifting rod then drops down into its normal longitudinal position and the brushes also drop down into their normal positions.

At the contacts 395, 222, the locking circuit of the relays 237, 213, 227 and the circuit of the cut off relay 9, (Fig. 13) of the called line are also opened, so that all the parts of the wanted line connector IX go back into their normal positions.

At the contact 221 the circuit extending back to the group selector through the test wire 202 is opened to deenergize the test relay 125 (Fig. 14). The group selector and the calling line connector are restored as soon as the calling subscriber replaces his receiver to deenergize the relay 100. The release relay 112 is then short circuited at the contact 119 and opens the contact 109. This interrupts the locking circuits of the relays 148, 123, 135, 131 and also the locking circuit of the test relay 125 if it should not have been already deenergized by the wanted subscriber having replaced his receiver. This would also cause the relay 250 of a wanted line connector to be deenergized so as to restore the wanted line connector.

By the closure of the contact 108 of the release relay the rotary magnet of the rotary control switch is energized by impulses flowing from the negative pole through the interrupter Ut, 108, 400, rotary magnet 172 to the positive pole. The rotary magnet then turns the brush lifting rod until it reaches its radial normal position in which the contact 400 is opened to interrupt the circuit of the rotary magnet.

At a contact 107 the restoring circuit of the calling line connector is closed, this circuit extending from the negative pole through the interrupter 156, rotary magnet 155, 401, 107, 402, 157 to the positive pole. The rotary magnet turns the brush lifting rod until it reaches the radial normal position in which the contact 157 is open. The brush lifting rod then drops down into its longitudinal normal position.

In order to give the calling subscriber a busy signal a busy tone device of a well known kind may be connected through a front contact on the relay 283 (Fig. 15) and a back contact of the test relay 293 of the wanted line selector and through a condenser to the wire 420. The busy tone current would then flow over the wire 201 to the calling subscriber, who would replace his receiver and deenergize the relay 269. This would result in the restoration of the wanted line selector to its normal position in the manner already described.

A ringing signal which indicates to the calling subscriber that a ringing current is actually flowing to the wanted subscriber could be periodically connected to the wire 130.

200 through a front contact on the relay 204.

From the foregoing description it will appear that the switches VI and VII, Fig. 5 14, may be called "calling-line-connecting-switches," and that the switches I, II, Fig. 13, are "calling-line-marking-switches" that electrically mark the calling lines to which the switches VI, VII shall connect. The 10 calling-line-connecting-switches VI, VII are prevented from connecting to improper marked lines by the switch V which is common to a group of calling-line-marking-switches.

15 The switches IX, Fig. 15, may be termed "wanted-line-connecting-switches," and the switches X, Fig. 15, "wanted-line-marking-switches." The switches IX, Fig. 15, are prevented from connecting to improper marked lines by the switch XII which is common to a group of wanted-line-marking-switches.

20

The contact strips a^1, b^1 and a^2, b^2 , Fig. 3, may be called "line contact strips."

25 The terms used in the three preceding paragraphs will be adopted in the following claims.

I claim:

30 1. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted to set the calling line connecting switches onto the calling lines marked by the calling-line-marking-switches, and a switch common to a group of wanted line marking switches and adapted to set the wanted line connecting switches onto the wanted lines marked by the wanted line marking switches.

35

40

45 2. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, switches for temporarily associating calling line marking switches with calling line connecting switches, and switches for temporarily associating wanted line marking switches with wanted line connecting switches.

50

55

60

65

3. In a telephone system, lines, calling means, calling-line-marking-switches for electrically indicating that a line is calling, switches for electrically marking wanted lines, panel-type calling-line-connecting-switches for connecting to calling lines, panel-type wanted-line-connecting-switches for connecting to wanted lines, a switch common to a group of calling line marking switches and adapted to set the calling line connecting switches onto the calling lines marked by the calling-line-marking-switches, and a switch common to a group of wanted line marking switches and adapted to set the wanted line connecting switches onto the wanted lines marked by the wanted line marking switches.

4. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, and interconnecting switches adapted to interconnect the calling line connecting switches and the wanted line connecting switches. 85 90 95 100

5. In a telephone system, lines, calling means, calling-line-marking-switches for electrically indicating that a line is calling, switches for electrically marking wanted lines, calling-line-connecting-switches for connecting to calling lines, wanted-line-connecting switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, and numerical interconnecting switches adapted to interconnect the calling line connecting switches and the wanted line connecting switches. 105 110 115 120

6. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted 125 126

to set the calling line connecting switches onto the calling lines marked by the calling-line-marking-switches, a switch common to a group of wanted line marking switches and adapted to set the wanted line connecting switches onto the wanted lines marked by the wanted line marking switches, and panel-type interconnecting switches adapted to interconnect the calling line connecting switches and the wanted line connecting switches.

7. In a telephone system, lines, calling means, calling-line-marking-switches for electrically indicating that a line is calling, switches for electrically marking wanted lines, panel-type calling-line-connecting-switches for connecting to calling lines, panel-type wanted-line-connecting-switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, and panel-type interconnecting switches adapted to interconnect the calling line connecting switches and the wanted line interconnecting switches.

8. In a telephone system, lines, calling means, calling-line-marking-switches for electrically indicating that a line is calling, switches for electrically marking wanted lines, panel-type calling-line-connecting-switches for connecting to calling lines, panel-type wanted-line-connecting switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, and numerical panel-type interconnecting switches adapted to interconnect the calling line connecting switches and the wanted line interconnecting switches.

9. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted to set the calling line connecting switches onto the calling lines marked by the calling-line-marking switches, a switch common to a group of wanted line marking switches and

adapted to set the wanted line connecting switches onto the wanted lines marked by the wanted line marking switches, trunks leading to the wanted line connecting switches, and combined numerical and trunk finding switches adapted to interconnect calling line connecting switches and trunks. 70

10. In a telephone system, lines, calling means, calling-line-marking-switches for electrically indicating that a line is calling, switches for electrically marking wanted lines, calling-line-connecting-switches for connecting to calling lines, wanted-line-connecting-switches for connecting to wanted lines, a switch common to a group of calling line marking switches and adapted to set the calling line connecting switches onto the calling lines marked by the calling-line-marking-switches, a switch common to a group of wanted line marking switches and adapted to set the wanted line connecting switches onto the wanted lines marked by the wanted line marking switches, trunks leading to the wanted line connecting switches, and panel-type combined numerical and trunk finding switches adapted to interconnect calling line connecting switches and trunks. 80

11. In a telephone system, lines, calling means, calling-line-marking-switches for electrically indicating that a line is calling, switches for electrically marking wanted lines, non-numerical calling-line-connecting-switches for connecting to calling lines, non-numerical wanted-line-connecting-switches 100 for connecting to wanted lines, a switch common to a group of calling line marking switches and adapted to set the calling line connecting switches onto the calling lines marked by the calling-line-marking-switches, and a switch common to a group of wanted line marking switches and adapted to set the wanted line connecting switches onto the wanted line marked by the wanted line marking switches. 110

12. In a telephone system, a plurality of lines, a group of switching devices operable in response to the initiation of a call on a line, a second group of switching devices operable in accordance with the designation of wanted lines, separate switching devices for establishing connections with calling and called lines, and switches common to said group and other switches common to said second groups of devices for controlling the operation of said switching devices. 115

13. In a telephone system, a plurality of lines, a group of switching devices, means operable in response to the initiation of a call on a line for actuating one of said devices to find the calling line, a second group of switching devices, means operable in accordance with the designation of wanted lines for operating one of said devices to select contacts representing the wanted line, 125 130

- separate switching devices for establishing connections with calling and called lines, and a switch common to said group and a switch common to said second group of devices for controlling the operation of said separate switching devices.
14. In a telephone system, a plurality of lines, a first group of switching devices operable in response to the initiation of a call, a second group of switching devices operable in accordance with the designation of called lines, a calling line connecting switch, a called line connecting switch, a switch common to the devices of the first group for operating the calling line connecting switch to connect with the line to which the first group has responded, and a switch common to the second group for operating the called line connecting switch to connect with the line in accordance with the designation of which the second group of devices has been operated.
15. In a telephone system, a plurality of lines, a first group of switching devices operable in response to the initiation of a call, a second group of switching devices operable in accordance with the designation of called lines, a calling switch, a called switch, common contacts for said calling and called switches with which said lines are connected, a switch common to the devices of the first group for operating the calling switch to connect with the contact of the line to which the first group has responded, and a switch common to the second group for operating the called switch to connect with the contact of the line in accordance with the designation of which the second group of devices has been operated.
16. In a telephone system, a plurality of lines, a first group of switching devices operable in response to the initiation of a call, a second group of switching devices operable in accordance with the designation of called lines, a calling switch, a called switch, a switch common to the devices of the first group for operating the calling switch to connect with the line to which the first group has responded, a switch common to the second group for operating the called switch to connect with the line in accordance with the designation of which the second group of devices has been operated, a test conductor common to said first group of devices and said calling switch, and a test conductor common to said second group of devices and said called switch.
17. In a telephone system, a plurality of lines, a connector switch having bank contacts connected to wanted lines, a wanted line marking switch comprising a group and an individual line selector, bank contacts for said line selector connected to certain bank contacts of said connector, means for operating said selectors in accordance with the designation of the wanted line, and means for operating said connector to seize a bank contact with which said individual line selector has connected.
18. In a telephone system, a plurality of lines, a connector switch having bank contacts connected to wanted lines, a selector switch associated with said connector switch operable in accordance with the tens numerical designation of the called line, a plurality of selector switches associated with said connector and operable in accordance with the units designation of the lines, means responsive to the operation of said first-mentioned selector switch for selecting one of said plurality of selector switches for operation, conductors leading from the contact banks of said plurality of selector switches to the contact bank of said connector switch, and means for causing said connector switch to engage a contact with which one of said plurality of selector switches has made connection.
19. In a telephone system, a plurality of lines, a connector switch for establishing a talking connection between calling and called lines, unit switches operable in accordance with the units designation of the called number for establishing a connection with the called line, a tens switch operable in accordance with the tens designation of the called number for selecting a units switch for operation, an automatic trunk selecting switch for associating said units and tens switches with said connector, and means for causing said connector to connect with a line with which an associated switch has connected.
20. In a telephone system, a plurality of lines, a connector switch for establishing talking connections with wanted lines, a tens and a units marking switch operable in accordance with the tens and units designations of the called number respectively, means responsive to the operation of the tens marking switch for selecting a units marking switch for operation and for operating said connector in accordance with the tens designation of the called line, and means responsive to the operation of the units marking switch for causing said connector to seize the called line.
21. In a telephone system, a plurality of lines, a connector having a contact bank in which said lines terminate, said contact bank being divided into a plurality of groups, a plurality of wipers for said connector adapted to cooperate with the various groups, a tens marking switch and a plurality of units marking switches, a selectively operable switching device for associating said marking switches with said connector, means for operating a tens marking switch in accordance with the tens numerical designation of the called line, means operative thereupon for selecting a certain set of contacts connected to wanted lines, a selector switch associated with said connector and operable in accordance with the units designation of the lines, means responsive to the operation of said selector switch for selecting one of said plurality of selector switches for operation, conductors leading from the contact banks of said plurality of selector switches to the contact bank of said connector switch, and means for causing said connector switch to engage a contact with which one of said plurality of selector switches has made connection.

- 5 nector brushes and a units marking switch for operation, means for operating the units marking switch in accordance with the units designation of the called line, and means 10 operative thereupon for causing said connector to seize with its selected brushes the called line.
- 15 22. In a telephone exchange system, a plurality of lines, calling and wanted line selectors, calling and wanted line connectors, two wires connected with each line extending through and used as line terminals in all said selectors and connectors, and a test wire for each line extending through and used as 20 a terminal in said calling line selectors and connectors.
- 25 23. In a telephone exchange system, a plurality of lines, calling and wanted line selectors, calling and wanted line connectors, and a test wire representing each line extending through and used as a terminal in 30 said calling line selectors and connectors.
- 35 24. In a telephone exchange system, a plurality of lines, calling and wanted line selectors, calling and wanted line connectors, two wires connected with each line extending through and used as line terminals in all said selectors and connectors, and a test wire for each line extending through and used 40 as a terminal in said wanted line selectors and connectors.
- 45 25. In a telephone exchange system, a plurality of lines, calling and wanted line selectors, calling and wanted line connectors, and a test wire representing each line extending through and used as a test terminal in 50 said wanted line selectors and connectors.
- 55 26. In a telephone exchange system, a plurality of lines, calling and wanted line selectors, calling and wanted line connectors, and two wires connected with each line extending through and used as line terminals in all said selectors and connectors.
- 60 27. In a telephone exchange system, a plurality of lines, calling and wanted line selectors, calling and wanted line connectors, two wires connected with each line extending through and used as line terminals in all 65 said selectors and connectors, a test wire for each line extending through and used as a terminal in said calling line selectors and connectors, and a second test wire for each line extending through and used as a terminal in 70 said wanted line selectors and connectors.
- 75 28. In a telephone exchange system, a plurality of lines, calling and wanted line connectors, a test wire representing each line extending through and used as a test terminal in said calling line selectors and connectors, and a second test wire representing each line extending through and used as a test terminal in 80 said wanted line selectors and connectors.
- 85 29. In a telephone exchange system, a plurality of lines, transitorily engaged calling line finders and wanted line selectors, calling and wanted line connectors, two wires connected with each line extending through and used as line terminals in said finders, selectors and connectors, a test wire for each line extending through and used as a terminal in 90 said finders and calling line connectors, and a second test wire for each line extending through and used as a terminal in said wanted line selectors and connectors.
- 95 30. In a telephone exchange system, a plurality of lines, transitorily engaged calling line finders and wanted line selectors, calling and wanted line connectors, two wires connected with each line extending through and used as line terminals in said finders, selectors and connectors, a test and a switch stopping wire for each line extending through and used as terminals in said finders and calling line connectors, and a second test and second switch stopping wire for each line extending through and used as terminals in 100 said wanted line selectors and connectors.
- 105 31. In a telephone system, a plurality of lines, selectively operable switching device, contacts for said device in which said lines terminate divided into groups a plurality of sets of movable contacts for said device each set arranged to cooperate with a certain group of contacts, and means for operating one set of movable contacts to cooperate with a plurality of groups of contacts.
- 110 32. In a telephone system, a plurality of lines, a selector switch, an impulse relay associated with said switch and responsive to impulses representing different digits of the called number, a release control relay for said switch, a changeover relay for said switch, resistances connected in series with said changeover relay and with said release relays, and contacts for said impulse relay for alternately short-circuiting said release relay and said changeover relay.

In testimony whereof I have signed this specification.

FRITZ ALDENDORFF.
